UNITED STATES PATENT OFFICE.

ALADAR HOLLANDER, OF BERKELEY, CALIFORNIA, ASSIGNOR TO BYRON JACKSON
PUMP MFG. CO., OF BERKELEY, CALIFORNIA, A CORPORATION OF CALIFORNIA.

VERTICAL-SHAFT TURBINE.

Application filed April 18, 1927. Serial No. 184,527.

My invention has for its principal object a turbine pump and direct connected electric motor or a turbine water wheel and direct connected generator adapted to rotate about a vertical axis wherein all of the radial stresses are substantially balanced and wherein the fluid pump, or fluid operated power turbine as the case may be, is mounted above the electrical unit and supported thereby and wherein there is a minimum number of bearings while maintaining the simplest possible construction of the entire equipment and the greatest accessibility to the various parts.

My invention is particularly adapted to large motor driven centrifugal pumps and by referring to the accompanying drawing in which such a unit is fully disclosed, my invention will be made clear.

Fig. 1 is an elevation partly in view and partly in section.

Figs. 2 and 3 are details in section and plan of an alternate form of gland.

Throughout the figures similar numerals refer to identical parts.

An electric motor is indicated by the numeral 1, supported upon the base 2 from the foundation 3.

On the opposite side of the motor is mounted the upstanding pump casing 4, with which is connected the inlet pipe 5 extending from the casing 4 and the discharge pipe 7 extending from the opposite side thereof.

Within the casing is the volute 9 which collects the pressure fluid discharged on the impeller 10 from which, due to the pressure imparted to it by the said runner, it is forced through the discharge pipe 7.

The impeller or fluid rotor 10 is keyed at 11 to the vertical shaft 12. The latter is conveyed through the glands 13 and 14.

The lower end of this shaft is provided with the coupling head 15, preferably forged thereon and which is adapted to engage by the concentric tongue and groove 16 to the coupling head 17 on the motor shaft 18.

The shaft 18 is carried in the radial guide bearing 19 on its lower end and the shaft 12 is carried in the radial and thrust bearing conventionally shown at 20, the shaft projecting therethrough and being supported

from the block 21 and nut 22, the latter engaging the shaft 12 by the threads 23.

It will thus be seen that although a separate shaft is provided for the pump and for the motor, the two, through the engagement of the coupling parts 15, 17 become, as far as their operation is concerned, the equivalent of an integral shaft.

The coupling halves 15, 17 are bolted together as by studs and nuts 24 and access thereto is had through the opening 25 in the housing 4.

The rotor of the motor 1, not shown but well known, is mounted upon the shaft 18 and drives the impeller 10 which by the pipe 5 is adapted to introduce fluid and deliver the same in the direction of the arrows 26, 26, 26, 26, to the suction or central openings of the impeller 10, which in turn, through its pump action discharges the fluid into the volute 9 and discharge pipe 7 in the conventional manner.

The unit may of course be positioned as desired with respect to the floor, but where employed in large structures, it will be found advantageous to position the floor as shown at 27.

Within the pump housing 4 is the diaphragm plate 28 provided with drain ledges 29-29 under the coupling 17 thus precluding any possibility of leakage water getting into the motor 1, as for example when the gland at 14 is being repacked.

The motor 1 provides the support for the entire pump structure and the bearing 19 at the end of the shaft 18 and the combined radial and downward thrust bearing 20 at the opposite or remote end of shaft 12 form the only necessary bearings for the combined pump and motor.

While I prefer to combine the radial and thrust bearing 20 at the top of the unit and the single radial bearing 19 at the bottom these may be reversed if desired, without departing from my invention.

Particular attention is directed to the packing gland shown generally by the numeral 14, and which is formed as a separate structure. This is seated on a faced recess on the inside of the housing 4 at 41, and secured by the externally accessible cap screws 42, 43.

Lifting eye bolts are shown at 44, 45 whereby upon breaking the joint at 33 and at 41, and removing the coupling bolts 24—24 at the joint 16 the entire top portion of the unit, with the rotating element including the shaft 12, impeller 10 and gland structure 14, may be lifted.

This enables ready access for repairs or replacement.

10 An alternate form of packing gland is shown at Figs. 2 and 3 wherein the gland plate is made parting on the joint 51, the two halves 52, 53 being bolted together by suitable bolts as 54.

15 Upon removing the cap screws 42, 43, as before and breaking the split joint 51, thus allowing the gland plates 52, 53 to be removed, the top and the entire rotating element down to the coupling joint at 16 may be removed and then by taking out the bearing parts 21, 22, the rotating element 10, 12 may be separated from the removed parts.

20 Either of the gland constructions shown in Fig. 1 or Figs. 2 and 3 are suitable, depending upon the size and local conditions available in any particular plant.

25 While my invention is particularly applicable to large centrifugal pump units it may also with advantage be employed for turbines for generating power from falling water.

If the water under pressure be delivered through the pipe 7, the apparatus as shown in the figure of the drawing would function as a turbine generating power in the electrical unit 1 and discharging the expended water through the pipe 5.

35 The coupling 15, 16, 17, it will be noted is positioned within the compartment 30, formed between the suction head 31 and the drain pan 28 and may be reached for inspection, repairs or replacement through the doorway 25.

40 The bearing 20 is supported from the cover 32 and is connected along the flange joint 33 with the pump housing 4. The compartment 34, accessible through the doorway 35 enables the operator to reach the gland 13.

45 By disconnecting at 33 and removing the bolts between the coupling flanges 15, 17, the entire rotating element and its surrounding casing may be lifted vertically from the housing 4.

50 By retaining the flange joint at 33 and breaking the flange joints at 36, 37, and 38, the entire hydraulic unit may be lifted vertically with the rotating element to get at the interior of the motor.

55 Access to the radial bearing 19 may be reached through the manhole 39.

60 It will thus be seen that all parts are accessible and may be easily and completely dis-assembled, including the separation of

the hydraulic and electric portions, housing and motor frame 2, while maintaining the shortest possible shaft, in a unit of minimum weight and greatest simplicity.

I claim:

1. A vertical shaft hydraulic machine in combination with an electric motor having a stator and a rotor and including a two part shaft, a radial bearing at one end of said shaft and a radial and thrust bearing at the other end of said shaft, a rigid flanged coupling between the two parts of said shaft, the rotor of said motor mounted on one of said parts and a fluid rotor mounted on the other of said parts, a casing having a volute therein, said volute having a suction inlet passage and a discharge outlet passage external to said volute and formed integral therewith, said casing having a flange connection to said stator, a cover member for said casing on the opposite side from said flange and having one of said bearings mounted thereon, said cover having a portion of the walls of one of said passages cast integral therewith. 70 80 85

2. A vertical shaft hydraulic machine in combination with an electric motor having a stator and a rotor and including a two part shaft, a radial bearing at one end of said shaft and a radial and thrust bearing at the other end of said shaft, a rigid flanged coupling between the two parts of said shaft, the rotor of said motor mounted on one of said parts and a fluid rotor mounted on the other of said parts, a casing having a volute therein, said volute having a suction inlet passage and a discharge outlet passage external to said volute and formed integral therewith, said casing having a flange connection to said stator, a cover member for said casing on the opposite side from said flange and having one of said bearings mounted thereon, said cover having a portion of the walls of one of said passages cast integral therewith. 90 95 100 105 110 115

3. Apparatus as set forth in claim 1 and a closure plate around one of said shaft parts and between said coupling and said stator. 120

4. Apparatus as set forth in claim 2 and a closure plate around one of said shaft parts and between said coupling and said stator. 125

5. In a vertical shaft centrifugal pump a casing having a base flange, a suction inlet with two branches, a volute member with a discharge outlet therefrom cast integral with and between said branches, an impeller mounted on an impeller shaft and 125 130

rotatable within the plane of said volute, a cover member adapted to close an opening in said casing through which said impeller is introduced and having a passage adapted to convey fluid from one of said branches to the central portion of said impeller and also having a shaft gland and a bearing, a second gland on the opposite side of said impeller mounted on a closure plate and a passage from the other of said branches to

the other central inlet portion of said impeller, an electric motor having a motor shaft and a flange coupling integrally connecting said shafts, a radial bearing, and a combined radial and thrust bearing one of said bearings supporting one end and the other bearing supporting the other end of said integral shafts remote from said coupling.

ALADAR HOLLANDER.
